MOUNTING MEANS FOR ROTATABLE DRUMS

Robert N. Birdsall, Elyria, Ohio, assignor to Link-Belt Company, a corporation of Illinois

Application April 15, 1957, Serial No. 652,908

1. Claim. (Cl. 308—203)

This invention relates to new and useful improvements in apparatus for rotatably supporting generally horizontally arranged cylindrical drums or kilns and deals more particularly with antifriction trunnions for rotatably mounting such bodies.

Trunnions for supporting drums of all types for rotation about horizontal or substantially horizontal axes should provide a minimum of frictional resistance to rotation of the drum. Further, the weight of each drum and its contents should be distributed as uniformly as possible on the trunnions to minimize wear, vibration and maintenance problems. An additional design feature to be considered is the ability to adjust the trunnions to quickly and easily align the drum in its desired position.

It is the primary object of this invention to provide apparatus for supporting a drum, or the like, for rotation about a substantially horizontal axis with a minimum of frictional resistance between the supporting apparatus and the drum.

A further important object of the invention is to provide apparatus for rotatably supporting a drum, or the like, with the weight of the drum and its contents so distributed as to prevent excessively large loads on any part of the support apparatus.

Still another important object of the invention is to provide apparatus for supporting a rotatable drum by rolling frictional engagement therewith, the apparatus being quickly and easily adjustable into proper relationship with the portions of the drum engaged thereby.

Other objects and advantages of the invention will be apparent during the course of the following description.

In the accompanying drawings forming a part of this specification and in which like reference characters are employed to designate like parts throughout the same,

Figure 1 is a side elevational view, partly broken away, of a rotatable drum support embodying the invention.

Figure 2 is a transverse sectional view taken on line 2—2 of Fig. 1 and illustrating one of the supporting assemblies for the drum.

Figure 3 is a sectional view taken on line 3—3 of Fig. 2 and showing the supporting assembly in top plan.

Figure 4 is a fragmentary sectional view taken on line 4—4 of Fig. 2.

Figure 5 is a fragmentary sectional view taken on line 5—5 of Fig. 2,

Figure 6 is a fragmentary sectional view taken on line 6—6 of Fig. 2, and

Figure 7 is a fragmentary sectional view taken on the line 7—7 of Fig. 2.

In the drawings, wherein for the purpose of illustration is shown the preferred embodiment of the invention, and first particularly referring to Fig. 1, there is shown a cylindrical drum 8 that is supported for rotation about a slightly inclined axis by two longitudinally spaced trunnion assemblies 9 and 11 which engage circumferentially extending tires 12 and 13 mounted on the drum.

Rotation is imparted to the drum 8 by a drive motor

14 which acts through a gear type speed reduction unit 15 and drive chain 16. The drive chain 16 is supported for movement in meshing relationship with the teeth of a segmental ring gear 17 that extends circumferentially around the cylindrical drum 8.

Referring now to Figs. 2 and 3 for a detail description of one of the trunnion assemblies, it will be seen that the base thereof includes a pair of spaced parallel beams 18 and 19 which are arranged to extend beneath and transversely of the drum 8. The opposite ends of the beams 18 and 19 are connected to the longitudinally extending stringers 20 which lie beneath and on opposite side portions of the drum 8. At the opposite end portions of each beam 18 and 19, there are provided bearing blocks 21 which rest upon the upper surface of their associated beam and are secured thereto by bolts 22 which extend through mounting pads 23 of the bearing blocks and through slots 24 in the upper flanges of the beam. The bearing blocks 21 at corresponding ends of the two beams 18 and 19 are axially aligned and their positions may be adjusted longitudinally of the beams 18 and 19 to the extent permitted by movement of the bolts 22 in the slots 24. Adjustment of the blocks 21 longitudinally of the beams 18 and 19 is accomplished by first loosening the bolts 22 for movement in the slots 24 and by then rotating the take-up bolts 25, which are threaded through abutments 26, into engagement with the outer sides of the bearing blocks. The bolts 22 are thereafter tightened to retain the blocks 21 in their positions of adjustment.

Journaled in the aligned bearing blocks 21 at corresponding end portions of the beams 18 and 19 are shafts 27 which span the space between their associated bearing blocks, as illustrated in Figs. 5 and 6. Each shaft 27 has mounted thereon a guide member 28 for pivotal movement about an axis paralleling that of the drum 8. Each of the two guide members 28 has an arcuately formed upper guide surface 29, the radius of curvature of which exceeds that of the tire 12 by a predetermined amount, as will be later described. The two guide surfaces 29 lie beneath and on opposite sides of the axis of the drum 8 and extend circumferentially of the tire 12. At each edge portion of each guide surface 29 there is provided a guide flange 31 as illustrated in Figs. 3, 5 and 7. Each flange 31 is continuous through a major portion of the length of the associated guide surface 29 being interrupted only at the center portion of the latter, see Fig. 3.

Extending around each guide member 28 is a series 50 of rollers 32 which are connected by side bars 33 and chain pins 33a to provide an endless chain. Each roller 32 has a diameter equal to the difference between the radii of curvature of its associated tire 12 and guide surface 29. In other words, when the drum 8 is positioned with a tire 12 resting on its rollers 32, the outer surface of the tire and the guide surface 29 will lie in spaced concentric relationship with each other and the rollers 32 will be arranged for movement between and in engagement with such opposed surfaces as the drum is rotated. Since the guide members 28 are free to partake of pivotal movement about the axes of their associated shafts 27, the limited adjustment of the bearing blocks 21 longitudinally of their associated beams 18 and 19 will not alter the concentric relationship between the guide surface 29 and the outer surface of the tire 12. Further, since the rollers 32 are not journaled for rotation about a fixed axis but are free to move through the space between the opposed guide surface 29 and tire 12, frictional forces tending to resist 65 rotation of the drum 8 will be reduced to an absolute minimum.

On each chain pin 33a is rotatably mounted a roller

32 which has a bearing bore a few thousandths of an inch larger than its pin to have some tolerance or radial play thereon. There is also a similar tolerance allowed between the side bar openings and the chain pins and between the ends of the rollers and the adjacent faces of the inside side bars of the links to allow for a substantial amount of transverse flexibility whereby, as seen in Figs. 1 and 6, the lower, or inactive, runs of these chains, during their free travel beneath their transversely tilted guide members, will flex into vertical planes. This affords greater flexibility and ease of adaptability to surfaces contacted, without galling or gouging the parts.

The above described structure of the trunnion assembly 9 is exactly duplicated in the trunnion assembly 11 and will not again be described, corresponding reference characters having been applied to the corresponding parts of the two trunnion assemblies. The trunnion assembly 9, however, includes in addition to the above described structure a pair of thrust rollers 34 and 35. As is best illustrated in Fig. 4, the thrust roller 34 is mounted on a shaft 36 which is journaled in bearings 37 at one side of the beam 19. Further, the diameter of the roller 34 is such that its periphery will engage the side of the tire 12 when the tire is radially aligned with and supported by the rollers 32.

The thrust roller 35 is mounted for rotation on a stub shaft 38 carried by a bracket assembly 39 which rests upon and is connected to the transverse beam 18. The periphery of the thrust roller 35 is arranged so as to provide a small clearance between it and the side of the tire 12 opposite the point of engagement between the roller 34 and the tire. The tire 12, therefore, moves between the two thrust rollers 34 and 35 when the drum 8 is rotated and engagement between the thrust rollers and tire will prevent any substantial axial movement of the drum on the supporting trunnion assemblies 9 and 11.

Mounted on the stringer 20 adjacent the opposite ends of the beams 18 and 19 are a pair of housing members 41 which substantially enclose the outer ends of the two guide members 28 and their associated chains of rollers 32. By reference to Fig. 2, it will be seen that one of the housing members 41 has mounted thereon a piece of flexible material 42 which is adjustable into engagement with the tire 12 for removing any foreign material therefrom before the tire is moved into engagement with the rollers 32.

Considering now the manner in which the trunnion assemblies 9 and 11 support the drum 8 with a minimum of frictional resistance to rotation of the drum, it will be readily apparent that the use of freely movable rollers 32 will completely eliminate any sliding engagement between the drum and its supports and that the pure rolling friction between the rollers and drum will provide the least possible frictional resistance to the rotation of the drum. Further, pivotal mounting of the guide members 28 upon which the rollers 32 move will

5 permit the guide members to adjust themselves to any irregularities in the drum 8 or tire 12 so that at least two rollers 32 on each guide surface 29 will engage and support the tire 12. It will also be apparent that adjustment of the two guide members 28 toward or away from each other in the manner described above, will permit very accurate distribution of the weight of the drum and its contents on the trunnion assemblies 9 and 11.

10 It is to be understood that the form of this invention herewith shown and described is to be taken as a preferred example of the same, and that various changes in the shape, size, and arrangement of parts may be resorted to without departing from the spirit of the invention or the scope of the subjoined claims.

15 Having thus described the invention I claim:

Apparatus for rotatably supporting a substantially horizontally arranged cylindrical drum, comprising an annular tire mounted on and extending circumferentially around said drum, a pair of elongated integral guide members radially aligned with said tire and disposed beneath said drum on opposite sides of the vertical plane 20 passing through the drum axis so as to be spaced circumferentially of said drum, each of said guide members having the upper peripheral portion thereof formed to provide an arcuately curved guide surface with a radius of curvature greater than that of said tire and guide flanges extending upwardly from opposite sides of said guide surface, means supporting each of said guide members for pivotal movement in the plane of said tire, said means including a shaft passing through the middle portion of the guide member and protruding outwardly from the opposite sides thereof in parallel relationship with the drum axis, and a bearing mounted on each side of the guide member in journaled relationship with the outwardly protruding portions of said shaft, an endless roller chain trained around the periphery of each guide member and between the guide flanges thereof for movement between the guide surface of said guide member and said tire, each roller of said chain having a diameter equal to the difference between the radii of curvature of said tire and said guide surface, means for adjusting the position of each bearing horizontally transversely of the drum axis to enable vertical and lateral adjustment of said drum axis by positioning the guide members supported by said bearings, and a pair of thrust rollers mounted for rotation on opposite sides of said tire to prevent substantial axial movement of the drum.
